United States Patent Office

Des. 198,545

Patented June 30, 1964

198,545

COMPARTMENTED PACKAGING CONTAINER

John Donald Bostrom, Niles, Ill., assignor to Poster
Packaging, Inc., Chicago, Ill., a corporation of Delaware

Filed Mar. 16, 1961, Ser. No. 64,337

Term of patent 14 years

(Cl. D58—13)

FIG. 4

FIG. 5

FIG. 2

FIG. 3

The lid or cover of the container which is shown in broken lines is plain.

The essential features of the design are shown in full lines.

I claim:

The ornamental design for a compartmented packaging container, as shown and described.
